PENDULUM ACTUATED ELECTRIC CLOCK

Leon Robert, Jullouville les Pins, France

Application December 20, 1948, Serial No. 66,331
In France January 16, 1948

1 Claim. (Cl. 58—30)

1
This invention relates to electric clocks wherein the pendulum is driven by the action exerted by an emissive coil on a magnetized bar. In such clocks it is essential to obtain the maximum isochronism of the oscillations.

Various devices have been hitherto proposed which provide means for applying a braking effect at the end of the oscillation to improve the above-mentioned isochronism. For this purpose, three-pole magnetized bars have been utilized, having two poles of the same sign at the ends and a third pole of the opposite sign in the middle.

Magnets have also been utilized, which are driven by an energizing coil secured at the rest position of the pendulum.

Such arrangements are only efficient when the positive resistances of the clock mechanism are very low. It is therefore necessary to overcome the resistances and the losses of inertia.

To overcome the disadvantages outlined above the present invention provides an electric clock wherein the braking action is obtained by the combination of a central coil mounted on the clock stand and cooperating with a three-pole magnet having spaced-apart recurvate, two poles of the same sign being positioned at the spaced-apart ends of said magnet while the third pole of opposite sign is positioned centrally of said magnet. The mechanism of the clock according to the invention is much simplified and necessitates but a very small number of wheels.

The oscillating movement of the pendulum ensures the tooth by tooth rotational drive through the intermediary of a special pawl control member, of a first wheel carrying a stud adapted to actuate the minute wheel, which is, while the hour wheel journaled freely on the minute wheel shaft, is frictionally driven at regular intervals by this shaft when the hour wheel is released from engagement with a locking device.

Other characteristic features of the invention will become apparent from the following description with reference to the accompanying drawing, in which:

Fig. 1 is a front view of the clock mechanism partly broken away to show details of construction, and

Fig. 2 is a side view of same.

Fig. 3 shows the manner in which the clock journals are mounted.

Fig. 4 is an enlarged perspective view of the driving mechanism for the hour hand.

The mechanism is supported by two plates 1 and 1'. The pendulum oscillates about a spindle 2 journaled in the aforesaid plates and com-

prises a rod 3 weighted at its lower portion by a counterweight of conical shape, formed from a plurality of washers such as 5. This particular shape of counterweight reduces resistance during the oscillatory movements.

The rod 3 carries under the counterweight a magnetized bar 6 having spaced-apart recurvate ends, as shown in Fig. 1, and having at 7, 7' two poles of same sign and at 7'' a pole of opposite sign.

The distance separating the two ends 7, 7' is equal to the length of a coil 8 which has its axis arranged horizontally and is secured to the clock casing or base member in a position corresponding to the rest position of the pendulum. The pendulum rod 3 is caused to oscillate by the periodic energization of the coil 8. Since the ends 7, 7' are of the same polarity, which is opposite in sign to the pole 7'', each will be driven out of the coil 8 upon its energization, i. e. this action will occur when either of the poles 7, 7' is in the coil 8, so that the oscillation of the pendulum is constantly energized.

The pendulum is arranged to drive either directly or, in the case of a large-size clock, by means of a fork member, a pawl 9 mounted on an arm 10 secured to the spindle 2 of the pendulum. This pawl 9 drives a toothed wheel 11. To prevent each oscillation of the pendulum from causing the wheel 11 to be driven on more than one tooth, the pawl 9 is fast, by a common connection with a strap 35 which pivots about a shaft 36, with a hook-shaped cam member 12 guided by a fixed pin 13 secured on the plate 1. Thus the engaging portion of the pawl 9 is lifted out of meshing engagement with the teeth when the wheel 11 has been rotated by a one-tooth interval. A lever 14, pivotally mounted about 15 carries a pin 37 which engages the teeth of the wheel 11 whereby the rotation of the wheel 11 will raise lever 14 which will connect by means of contact element 38, on reaching its uppermost position, the terminal contacts of the wires 16, 17 inserted in the circuit for energizing the coil 8. These wires may be concealed within the clock casing on their remaining path.

The wheel 11 is fast with a pin 18 meshing with the teeth of a wheel 19 so as to rotate the latter. A retaining pawl 20 is provided in order to limit the rotational movement of wheel 19.

The shaft 21, carrying the wheel 19, also carries an eccentric cam 22 and the minute hand 23. The hour hand 24 is fast with a sleeve 25 on

which a ratchet wheel 26 is secured. The sleeve 25 is loosely mounted on the shaft 21.

A vertically arranged fork 28 is pivoted on another shaft 27; this fork has at the end of each prong thereof a pair of pins 29 adapted to mesh with the teeth of the ratchet wheel 26.

As shown in Fig. 4, an eccentric cam 22 mounted upon the shaft 21 is positioned for rotation between the prongs of a fork member 28. The fork member 28 carries pins 29 which are adapted alternately to engage the teeth of ratchet wheel 26 to hold it against rotation by frictional engagement with the shaft 21. Rotation of the eccentric cam 22, which is effected by the rotation of shaft 21, causes the fork member 28 to reciprocate laterally and to release, at regular intervals, one of the pins 29, thereby permitting the ratchet wheel 26 to rotate and then effects re-engagement of the other pin 29 with the teeth of the ratchet wheel to hold the wheel against rotation until the next periodic release.

This will cause the hour hand 24 to rotate at regular intervals. With the arrangement described one of the gearings of the conventional clock mechanism may be dispensed with.

To reduce frictional losses between shafts and their journals, the latter are made of simple cylindrical members such as shown at 30 in Fig. 3. These cylinders engage hollow sleeves screw-threaded externally so as to be screwed into the plates. A set-pin 31 is provided for acting as a counter-pin to the end journal pin of the shaft 30.

The clock casing is formed by two uprights of any suitable material such as wood, provided with grooves, as at 32, for receiving both in the front and back faces of the mechanism, glass plates 33, 34 adapted to prevent dust or other foreign substances from penetrating into the mechanism. The front glass plate 33 acts as a dial. This plate may be provided with the conventional marks either by engraving or other mechanical or chemical action applied to the glass surface, or by adhesively secured signs of paper or other material.

It will be readily understood that the embodi-

ment described hereinabove and illustrated in the accompanying drawing is merely given by way of example without any purpose of limitation as to shape, size, arrangement, material utilized, etc. 5 Various modifications may be brought to the details of the apparatus without impairing or exceeding the scope of the invention.

What I claim is:

10 An electric clock comprising a pendulum, electrically-energized means for oscillating said pendulum, a minute wheel fixedly mounted on a shaft, a first toothed wheel provided with a pin in driving engagement with the said minute wheel, a toothed hour wheel having circumferentially disposed teeth and rotatably mounted upon said shaft and rotatable by frictional engagement with said shaft, a vertically disposed fork member having spaced-apart prongs pivotally mounted about a fixed point below the said shaft and carrying adjacent the ends of said prongs a pair of pins engageable between the teeth of said hour wheel, an eccentric cam member mounted on said shaft between the spaced-apart prongs and engageable with the sides of said prongs to cause a regular oscillating movement of said forked member upon rotation thereof, and a pawl control means actuated by said pendulum and actuating in turn in a tooth by tooth manner said first toothed wheel.
